US0D1016361S

(12) **United States Design Patent** (10) **Patent No.:** **US D1,016,361 S**
(45) **Date of Patent:** **** Feb. 27, 2024**

(54) **LINEAR LUMINAIRE**

(71) Applicant: **Eaton Intelligent Power Limited**,
Dublin (IE)

(72) Inventors: **Christopher Ring**, Derry, NH (US);
Christopher G. Henley, Pittsburgh, PA (US); **Arkadiusz Oskar Doroz**, Syracuse, NY (US); **Virginia Merriam**, Clay, NY (US); **Gangadhar Mestri**, Dharwad (IN)

(73) Assignee: **EATON INTELLIGENT POWER LIMITED**, Dublin (IE)

(**) Term: **15 Years**

(21) Appl. No.: **29/798,726**

(22) Filed: **Jul. 9, 2021**

(51) **LOC (14) Cl. 26-04**

(52) **U.S. Cl.**

USPC **D26/76**

(58) **Field of Classification Search**

USPC D26/24, 51, 60, 63, 72-83, 89, 118, 120, D26/138

(57) **CLAIM**

The ornamental design for a linear luminaire, as shown and described.

DESCRIPTION

FIG. 1 is a bottom perspective view thereof;

FIG. 2 is a top perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and

FIG. 8 is a right side view thereof; and,

FIG. 9 illustrates a bottom perspective view of the linear luminaire showing a light engine of the linear luminaire in an open position.

The broken lines are used in the drawings to illustrate features of the linear luminaire that form no part of the claimed design. The drawings contain dash-dot symbolic break lines in FIGS. 1-6 and 9. The break lines and any portion of the article between the break lines forms no part of the claimed design.

1 Claim, 6 Drawing Sheets
